Primary Examiner—Carol Rademaker

(57) **CLAIM**

The ornamental design for a bottle, as shown and described.

DESCRIPTION

FIG. 1 is a perspective view of the bottle of our new design as seen from the top, front, and right sides;

FIG. 2 is a front elevational view thereof, the rear elevation being a mirror image, except for the unclaimed threads;

FIG. 3 is a left side elevational view thereof, the right side elevation being a mirror image, except for the unclaimed threads; and,

FIG. 4 is a top plan view thereof.

The broken lines shown in the drawings are for illustrative purposes only and form no part of the claimed design.
